UNITED STATES PATENT OFFICE.

FREDERICK P. BROOKS, OF NORWICH, NEW YORK.

DESIGN FOR A CHAIR.

SPECIFICATION forming part of Design No. 19,573, dated January 14, 1890.

Application filed November 21, 1889. Serial No. 331,127. Term of patent 7 years.

To all whom it may concern:

Be it known that I, FREDERICK P. BROOKS, of Norwich, in the county of Chenango, and in the State of New York, have invented a certain new and useful Design for Chairs; and I do hereby declare that the following is a full, clear, and exact description thereof, reference being had to the accompanying drawings, in which—

10 Figure 1 is a perspective view of a chair of my design, and Figs. 2 and 3 are front and side elevations of the same.

Letters of like name and kind refer to like parts in each of the figures.

15 The principal feature of my design consists in the general shape of the side of the chair, the same being composed of a straight back, post A, a downward, forward, and upward curved side rail B, and an upward and rearward curving arm C, which extends between the front end of said side rail and said back post. Said side rail rests upon an oppositely curved base-rail D, all substantially as shown.

Another feature of my design consists in 20 the general shape of the front of my chair, which front is composed of the vertical back posts A and A, horizontal cross-rails a and a,

curved side rails B and B, curved arms C and C, horizontal seat-stretchers F and F, extending horizontally between the lower ends of 30 said back posts and said arms, the seat G, resting upon said stretchers, and the curved base-rails D and D, connected by horizontal rungs d and d, all substantially as shown.

Another and the last feature of my design 35 consists in the general shape of the chair, which is composed of the back posts A and A, cross-rails a and a, curved side rails B and B, curved arms C and C, stretchers F and F, seat G, curved base-rails D and D, and connecting-rungs d and d, all substantially as shown.

Having thus described my invention, what I claim is—

The design for a chair, substantially as 45 shown.

In testimony that I claim the foregoing I have hereunto set my hand this 21st day of October, 1889.

FRED. P. BROOKS.
